UNITED STATES PATENT OFFICE

BERNARD FEINGOLD, OF NEW YORK, N. Y.

DISH DRAINER

Application filed April 25, 1929. Serial No. 357,933.

This invention relates to dish drainers. The drainer according to this invention is so constructed that it automatically adjusts itself to different sizes of dishes. It opens 5 up to accommodate the larger dishes and can be folded up when not in use.

These and other objects will become apparent upon a further study of the description and drawings in which Fig. 1 is a plan 10 view of the drainer, Fig. 2 is a section of the drainer taken along the line 2—2 of Fig. 1 showing the drainer in open position to accommodate the smaller dishes, the dotted line indicating a portion of a small 15 dish in supported position, Fig. 3 is a partial section taken also along the line 2—2 of Fig. 1 but showing the drainer in a wider open position to accommodate the larger dishes, the dotted line indicating a portion 20 of a large dish, and Fig. 4 is a section also along line 2—2 but showing the drainer in folded position.

The drainer consists essentially of two oppositely disposed pivotally mounted wire 25 rack frames. Each of these rack frames has a heavy lower bar 5 and a somewhat lighter U shaped bar 6 having its arms 7 fastened to bar 5 near its ends. Intermediate of the arms 7 are a plurality of still 30 lighter bent cross bars 8 having one end fastened to bar 5 and the other end to bar 6. The arms 7 which are in effect end cross bars of their corresponding rack frame, are bent similarly to bars 8. The ends of bar 5 35 for one rack frame are pivotally mounted in supporting plates 9, while the ends of bar 5 for the other frame are pivotally mounted in supporting plates 10. Each pair of plates 9 and 10 are pivotally connected to 40 each other by means of a rivet 11. Each plate 9 has an outer supporting leg 12 and an inner supporting leg 13, while each plate 10 has an outer supporting leg 14 and an inner supporting leg 15. The upper edge 45 of each plate 9 is provided with a lug 16 projecting laterally into the path of its adjacent arm 7 as said arm is swung with the rest of its frame from its inner position outward. In a similar manner plates 10 50 are provided with lugs 17 which project

into the paths of their adjacent arms 7. Each arm 7 is provided with an inwardly projecting bent wire guard 18 fastened to it.

For holding the smaller dishes, one of which is indicated in part by the numeral 55 19, Fig. 2, the supporting plates 9 and 10 have their legs 12, 13, 14 and 15 in contact with the supporting surface upon which the drainer stands. The rack frames are held from rotating outwardly by lugs 16 and 17. 60

For holding the larger dishes, one of which is indicated in part by the numeral 20, Fig. 3, bars 6 are rotated away from 65 each other, which causes arms 7 to press against lugs 16 and 17, thereby raising legs 13 and 15 from the supporting surface, resulting in the drainer being supported only by legs 12 and 14 of the supporting plates. The weight of the dishes and their frictional contact with the inner side of bars 70 6 holds the drainer in open position.

Guards 18 at the end of the rack frames (Fig. 1), are provided to prevent cups or other rounded utensils from falling out the drainer at the ends. Cross bars 8 have a 75 bend in them, so that they extend from bars 6 inwardly and then bend downwardly to their connection with lower bars 5. The bend is a very useful feature. It permits upper bars 6 to be separated widely for 80 large dishes, while cross bars 8 remain close enough together to hold up smaller dishes between them.

In order to fold the drainer when not in use, bars 6 are brought towards each other 85 and each pair of supporting plates 9 and 10 are turned down towards each other bringing their legs 12 and 14 together as shown in Fig. 4. Although bars 8 and arms 7 are shown on line opposite each other in Fig. 1, the rack frames can fold into each other as shown in Fig. 4, because of the play at the 90 pivotal connections between bars 5 and plates 9 and 10. Instead of taking into account this play, the bars 8 and arms 7 of their respective frames can be offset on their 95 respective bars 5 so as to clear each other when the drainer is folded.

I claim:

1. A dish drainer comprising a pair of 100

oppositely disposed rack frames, each frame comprising an upper and lower bar connected to each other by a plurality of cross bars spaced at intervals along the length of the frames, and supporting means for each frame, the supporting means for one frame being pivotally connected to the supporting means of the other, said lower bars being pivotally mounted upon their corresponding supporting means on opposite sides of the pivotal connection of the supporting means.

2. A dish drainer comprising a pair of oppositely disposed rack frames, each frame comprising an upper and lower bar connected to each other by a plurality of cross bars spaced at intervals along the length of the frames, said cross bars having a bend in them causing said bars to extend from the upper bar inwardly and then downwardly, and supporting means upon which the lower bar of each frame is pivotally mounted, the bend of the cross bars of one frame passing below the upper bar of the other frame when said frames are folded together about their pivotal axes.

3. A dish drainer comprising a pair of oppositely disposed rack frames, a support for each frame near each end thereof upon which the frame is pivotally mounted substantially at its bottom, the supports of one frame being pivotally connected to the supports of the other, the pivotal axes of said frames and supports being substantially parallel to each other and the pivotal axes of said frames being located on said supports on opposite sides of the pivotal connections of said supports, and laterally projecting lugs upon said supports projecting in the path of said frames when said frames are swung outwardly, whereby swinging said frames outwardly raises the pivotal connections of the supports.

4. A dish drainer comprising a pair of oppositely disposed rack frames, a support for each frame upon which its corresponding frame is pivotally mounted, said supports being pivotally connected to each other, the pivotal axes of said frames and supports being substantially parallel to each other, the pivotal axes of said frames being located on said supports on opposite sides of the pivotal connection of said supports, and laterally projecting lugs carried by the upper part of said supports and located outside of and above the pivotal axes of said frames, said lugs projecting into the path of said frames when said frames are swung away from each other.

5. A dish drainer comprising a pair of oppositely disposed rack frames, and a support for each frame near each end thereof upon which the frame is pivotally mounted, the supports of one frame being pivotally connected to the supports of the other, the pivotal axes of said frames and supports be-

ing substantially parallel to each other, the pivotal axes of said frames being located on said supports on opposite sides of the pivotal connections of said supports, each support comprising an outer and inner leg adapted to contact with the surface upon which the drainer stands when the drainer holds small dishes, said inner legs being raised from said surface when said frames are swung outward for holding large dishes.

6. A dish drainer as claimed in claim 1 comprising guards on the end cross bars, the guards on the end cross bars of one frame projecting inwardly toward the guards on the end cross bars of the other frame.
